UNITED STATES PATENT OFFICE.

ELIZABETH A. DEGAN, OF HARTFORD, CONNECTICUT.

DESIGN FOR A STICK-PIN.

47,713.

Specification for Design. Patented Aug. 17, 1915.

Application filed July 5, 1913. Serial No. 777,588. Term of patent 14 years.

To all whom it may concern:

Be it known that I, ELIZABETH A. DEGAN, a citizen of the United States, residing at Hartford, in the county of Hartford and State of Connecticut, have invented a new, original, and ornamental Design for a Stick-Pin, of which the following is a specification, reference being had therein to the accompanying drawing.

The figure is a plan view of a stick pin, showing my new design.

I claim:

The ornamental design for a stick pin, as shown.

In testimony whereof I hereunto affix my signature in presence of two witnesses.

ELIZABETH A. DEGAN.

Witnesses:

THOS. S. DEGAN,
HARRY E. BACK.
